WINDOW SHADE

James S. Mead, Rising Sun, Ind.; Rising Sun State Bank administrator of said James S. Mead, deceased

Application September 28, 1936, Serial No. 102,925

5 Claims. (Cl. 156—27)

My invention relates to window shades of the type which are rolled on spring rollers having the usual releasable stop mechanism and mounted vertically over a window so that when the shade is unrolled it will cover all or a portion of the window itself. My novel window shade is the type which may be unrolled to cover a portion of the window and/or which may be bodily moved together with its roller vertically up and down the face of the window, so that the shade may cover a portion of the window, as for example, the center or bottom portion while leaving the upper portion uncovered. Window shades of this type have been on the market but the controls are usually extremely complicated and necessitate at least two individual sets of controls one for unrolling the shade and the other for moving the shade as a whole vertically up and down the window.

It is an object of my invention to provide a window shade of the above described type which may be either unrolled or moved bodily up and down the window by grasping a single cord attached to the center or bottom edge of the window shade alone.

It is a further object of my invention to provide a window shade having the above advantages and characteristics but which may be cheaply and easily constructed, and, for the most part, composed of rollers or portions thereof which are now on the market and which are typical of the usual spring shade roller now in use.

It is a further object of my invention to provide a window shade of the above type which may be easily installed and adjusted by the purchaser and which will withstand a great amount of abuse without injury or the necessity of complicated readjustments.

Another object of my invention is to provide a window shade with all of the above characteristics which in appearance looks like the ordinary window shade which may not be moved bodily up and down the window, and which when moved bodily down the window does not cut out any of the light coming through the window above the shade, and does not possess unsatisfactory adjusting means, etc., for controlling the action of the shade.

These and other objects of my invention which will be set forth hereinafter or will be apparent to one skilled in the art upon reading these specifications, I accomplish by that certain construction and arrangement of parts of which I shall now describe a preferred embodiment. Reference

is now made to the drawing which forms a part hereof, and in which:

Figure 1 is a front view of my novel window shade installed on a typical window.

Fig. 2 is a cross section of one end of the lower roller of my novel window shade.

Fig. 3 is a sectional view of my lower window shade roller taken on the section line 3—3 of Fig. 2.

Fig. 4 is the same section as illustrated in Fig. 10 but with the lower window shade in its locked position which prevents its further unrolling.

Fig. 5 is a section of the other end of my window shade roller taken on the section line 5—5 of Fig. 1.

Fig. 6 shows a modification of my novel roll pintle illustrated in Fig. 3.

Fig. 7 is a perspective view of the bracket for holding my lower window shade roller.

Fig. 8 is a cross section of a modification of my novel roll and frame.

Briefly, in the practice of my invention, I provide the usual window shade roller positioned and held in the usual window shade roll holder at the top of my window, and instead of winding the window shade itself upon this roller, I wind two straps at the ends thereof so as not to interfere with the open portion of the window. Upon the end of these two straps I hang a frame in which is positioned a second window shade roller carrying the shade itself with the re-roll spring having less tension than the re-roll spring in the upper roller. One end of the lower roller is provided with spring means and a revolving pawl which revolves with the roller, together with a stop which abuts the pawl when the window shade is pulled at an angle to the vertical, and hence prevents the shade roller from unrolling, and in effect, unrolls the straps on the first roller. In the event the window shade is pulled directly downward or in the vertical, the shade itself will unroll on its roller but the straps will not unroll on the first roller because the spring tension is greater.

Referring to the drawing, I provide the usual type of spring shade roller 1, having the usual type of releasable stops 2 and the re-roll spring 3, and I mount this in the typical window shade roller brackets 4 on the window frame 5. Around this roller and at each end I wind a strap 6 and provide disc-like shoulders or guides 7 therefor, to insure the even rolling of the straps. Hung on the end of these straps 6 is a frame generally indicated at 13, composed of two end brackets 8 and 8' having slots 8a in an upwardly projecting

tongue portion 9. The body portion of the bracket 8 is cut out to hold a typical spring window shade roller with the flattened wind pindle 10 and the round pindle 11. The two brackets 8 and 8' are held in position and spaced apart by a joining rod 12 which may be fastened to the two brackets in any manner well known in the art.

Positioned and held in this frame 13 is a second window shade roller 14 having the usual re-wind spring 15 but wound to give less tension than the re-wind spring 3 in the roller 1. The end opposite to the re-wind end of the roller 14 is hollowed out as at 16. Within this hollow is placed a plug 17 and a plug 18 spaced therefrom. There is an aperture in the center of the plugs 17 and 18 and a rod 19 of resilient material is placed in the apertures in the plugs. The plug 17 is preferably held stationary within the hollow 16 while the plug 18 may be slid to different positions within the hollow 16. The rod 19 projects beyond the end of the roll 14 and is of a much less diameter than the diameter of the hollow portion 16. The plug 18 is positioned along the rod 19 so as to give an adjustable but determined spring tension to the end 19a of the rod 19. Attached to the end of the roller 14 and surrounding the rod 19 is a disc 20. This disc has an aperture 21 of much greater diameter than the diameter of the rod 19 and is so positioned that the rod end 19a projects through the aperture 21. The disc 20 is rigidly fastened to the end of the roller 14 so that it revolves therewith. The periphery of the disc 20 is cut 35 to form pawls 22. While I have shown two pawls in my preferred embodiment, it is apparent that any number of pawls from one on, may be used in practicing my invention. The pawls 22 are so configured on the periphery of the disc 20 that when the roller 14 is in its horizontal position or is concentric with the horizontal line of the frame 13, the pawls will revolve freely. If, however, the end of the roller 14 carrying the spring rod 19 is pulled downwardly in the frame 13 the pawls 22 will abut the rod 12 and prevent the roller 14 from further unrolling. This is well illustrated in Fig. 3 which shows the roller 14 and the disc 20 concentric to the end 19a of the rod 19, while Fig. 4 shows the disc 20 and the roller 14 eccentric to the end 19a of the rod 19 and with the pawl 22 abutting the rod 12.

In my preferred form I prefer to use a disc 20 having but two pawls 22, and position these pawls in such a manner that they will contact the rod 12 just after the latches 2 lock the roller from reversing or rolling. I do not intend to limit myself to this construction but gain an advantage inasmuch as when the roller is pulled down so the pawls are contacted and released the shade 25 will only re-roll a very short distance. I do not intend to limit myself to the brackets 8 which I have illustrated and described, since numerous other types of brackets or frameworks may be used in carrying out my invention, but the slots 8a which I have shown permit the straps 6 to be adjusted as to length, as is well illustrated in Fig. 7.

The modification illustrated in Fig. 6 shows the spring rod 19 mounted in a tube 26 terminated in a solid plug 27 with the rod 19 permanently positioned in the center of the plug 27. I provide a second plug 28 having a central aperture 29 through which the rod 19 is journaled in such a manner that the plug 28 may be slid in and out of the tube 27 in order to lengthen or shorten

the free end 19a of the rod 19, and thus to change its tension. I preferably provide a small aperture 30 in the face of the plug 28 which permits the insertion of a hook in order to pull the plug 28 out of the tube 26. This tube 26 with its complete assembly is slid into the hollow 16 at the end of the roller 14 in such a manner that it may be easily removed therefrom and the tension of the rod 19 changed and then replaced.

The modification illustrated in Fig. 8 shows a means for resiliently maintaining the roller 14 in a horizontal position and so that a lateral pull of the shade will tip it and prevent its further unrolling. The modified form comprises a frame 35 having the connecting bar 12. There is a vertical slot 36 in this frame in which rides a collar 37 supported by a spring 38. At the top of the frame 35 are a series of slots 39 which support one end of the spring. It is apparent that by attaching the spring end to the different apertures 39, the pull or tension on the collar 37 may be regulated. The roller end has the disc 20 carrying the pawls 22 which abut the rod 12 when the roller 14 is tilted out of the horizontal. In some cases the construction is beneficial over the others, since the roller 14 need not be drilled out nor mutilated in any way and the disc 20 may be tacked or nailed on the end.

The free end of the shade 25 carried by the roller 14 may be terminated by a shade stick in the usual manner and with a pull cord 31 positioned in its center.

From the above description the action of my window shade is as follows: If the operator desires to unroll the shade 25 on the roller 14 he pulls the shade pull 31 directly downwardly or in a vertical direction. By pulling it in this way the downward pressure on the roller 14 is evenly distributed and the disc carrying the pawls 22 is not pulled down but revolves concentrically around the rod 19 and the pawls 22 do not abut the rod 12 as is illustrated in Fig. 3. This permits the shade 25 to unroll on the roller 14, since the re-wind spring 15 in the roller 14 is weaker in tension than the re-wind spring 3 in the roller 1, in the same manner that a normal shade will do. When the shade 25 has been pulled as far as is desirable, the latches 2 will prevent the re-rolling of the shade as is well known in the art. Now, if the operator should desire to pull the whole shade together with the roller 14 downwardly on the window in order to open a space above the shade, he grasps the shade pull 31 and pulls it in a direction diagonal to the vertical in the direction of the arrow 35. This places the downward pull on the roll 14 at the end having the spring rod 19 and bends the rod 19 against its tension in such a manner that the disc 20 carrying the pawls 22 will attempt to revolve eccentrically around the rod end 19a and the pawls 22 will abut the rod 12 and prevent further unrolling of the roll 14. As this pressure is continued the tension in the re-wind spring 3 is overcome and the straps 6 are unrolled from the roller 1, thus lowering the frame 13, the roller 14 and the whole shade 25. It is apparent from the above that by manipulating the shade pull 31 either in the vertical or in the diagonal, the shade may be re-rolled on the roller 14 (by manipulating the shade pull in the vertical), or the whole shade and roller 14 may be raised up (by manipulating the shade pull in the diagonal). In both of these cases the action of re-rolling is the same as on the typical shade well known in the art, that is with a slight forward or down-

ward pull to release the stops 2 before permitting a rather rapid re-roll.

I wish particularly to call attention to the cheapness of making my device. The roller 1 is 5 preferably a shade roller of the ordinary type, although I do not intend to limit myself to this, since numerous other types of rollers may be made to carry out my invention. The roller 14 is a shade roller of the usual type, excepting as to the hollowed out end 16 carrying the resilient rod 19 and the disc 20 carrying the pawls 22. Numerous forms of my frame 13 may be made 10 and numerous means for stopping the revolving of the disc 20 may be associated with the frame.

In using my invention, I may preferably house 15 the roller 1 with all of its parts and permit the straps 6 to come through a slot or slots therein. I may also house both of the rollers when they are at the top of the window leaving an opening at 20 the bottom of the housing which permits the entry and exit of the roll 14 together with its frame 13. I may find it preferable to mount the roller 1 in the back of the window, run the straps 25 6 over rollers or pulleys and through slots in the window frame itself, or I may prefer to use cords in place of the straps 6.

It is to be understood that different forms of my preferred form may be made without departing from the spirit of my invention.

Having thus described my invention, what I 30 claim as new and desire to secure by Letters Patent, is:

1. A window shade comprising a spring roller having a releasable stop, straps wound around 35 said roller with their ends supporting a frame, a second spring shade roller having a releasable stop supported in said frame, a window shade wound around said second roller, the spring in said first roller being of greater tension than the 40 spring in said second roller and means which inhibit the unrolling of the shade when the shade is pulled at an angle to the vertical, said inhibiting means comprising a means for resiliently maintaining the second roller in a horizontal position and means inhibiting the unrolling of said 45 second roller when it is out of the horizontal position.

2. A window shade comprising a spring roller having a releasable stop, straps wound around 50 said roller with their ends supporting a frame, a second spring shade roller having a releasable

stop supported in said frame, a window shade wound around said second roller, the spring in said first roller being of greater tension than the 5 spring in said second roller and means which inhibit the unrolling of the shade when the shade is pulled at an angle to the vertical, said inhibiting means comprising a spring for resiliently maintaining this second roller in a horizontal position, and a pawl on said roller and a stop, said pawl abutting said stop only when said roller is 10 out of the horizontal position and prevents its unrolling.

3. In a spring shade roller having a releasable stop and mounted horizontally in a holder, means 15 for preventing the unrolling of the same comprising a pawl projecting outwardly from the periphery of the roller and a stop associated with the holder, said pawl being out of contact with said stop when said roller is in a horizontal position, but abutting said stop when said roller is 20 out of the horizontal position and means for resiliently holding said roller in its horizontal position.

4. In a spring shade roller mounted in a frame, at least one bearing shaft comprising a spring 25 rod mounted in a hollowed end of said roller and journaled at a point within said hollowed end so as to form a resilient bearing shaft, a disc mounted on the end of said roller with said resilient shaft projecting through an opening therein of 30 greater diameter than the diameter of said shaft, at least one pawl on the periphery of said disc, an abutment on said frame out of contact with said pawl when said resilient bearing is unflexed but contactable by said pawl when said resilient bearing is flexed.

5. In a spring shade roller mounted in a frame, at least one bearing shaft comprising a spring rod mounted in a hollowed end of said roller and journaled at a point within said hollowed end 40 so as to form a resilient bearing shaft, a disc mounted on the end of said roller with said resilient shaft projecting through an opening therein of greater diameter than the diameter of said shaft, at least one pawl on the periphery of said 45 disc, an abutment on said frame out of contact with said pawl when said resilient bearing is unflexed but contactable by said pawl when said resilient bearing is flexed, and means for adjusting said journal point along said rod.

JAMES S. MEAD.
